UNITED STATES PATENT OFFICE

JAMES F. MACWILLIAMS, OF CRESSON, PENNSYLVANIA

SAFETY SWITCH STRUCTURE

Application filed March 21, 1928. Serial No. 263,457.

The present invention pertains to improvements in switch structures and has for its principal object the promotion of the factor "safety" throughout its operable details.

5 An important object is to provide switch structure for controlling electrical circuit, which includes a housing having an open side and a cover for said open side which can only be removed after the switch contacts have 10 been disengaged.

Another object is to provide switch structure of the above character which includes 15 means for maintaining the switch contact disengaged when the operating means employed have been detached therefrom.

Still another object resides in the provision 20 of novel lock means for maintaining the switch element in contacting position, and at the same time locking the cover to the housing securely and against possibility of removal, excepting when the switch element is moved to open position.

Other novel and advantages will become 25 apparent as the invention is better understood from the following specification and claims.

In the drawings:—

Figure 1 represents a cross sectional view 30 through the switch structure, and disclosing the details thereof in sectional view.

Fig. 2 is a sectional view on the plane with the open side of the housing, disclosing the position of the contact carrier shown in disengaged position, and

Fig. 3 represents a perspective view of the 35 slidable contact carrier.

Now for a more specific description of this invention, reference is made to the drawings wherein like numerals designate like parts. A housing 1 of rectangular box-like structure,

40 is open at one side, and provided with a tubular nipple 2 projecting from its opposite side.

One end of the housing is provided with a boss 3 having a bore extending from its outer end, and communicating with the interior of 45 the housing, while a hollow projection 4 is provided at the opposite end of the housing, and in substantial alinement with the boss 3.

A block 5 of insulating material, is arranged within the housing in the manner 50 clearly shown in Fig. 1. This block is formed

with a pair of spaced openings adapted to receive a fuse member or cartridge 6.

The conductor wires 7 may be led through the tubular nipple 2 at one side of the housing. The cover which is generally referred to by numeral 8, comprises a plate 9 provided with a depending rectangular flange 10 which is adapted to fit snugly within the open side of the housing 1. The cover is provided with a laterally projecting flange 11 which engages 55 over the open edge of the housing for protective purposes. The top side of the cover is provided with an upstanding nipple 12 thru which the conductors 13 are led.

As is clearly shown in Fig. 1, a block of insulating material 14 is secured within the flanged area of the cover, and formed throughout its length with a bore 15. A pair of spaced contact members 16 are secured 60 within the block 14, so that their outer ends are normally in contact with the respective ends of the fuses 6.

A pair of contact members 17—17 are embedded in the block 14 and spaced from the respective contacts 16 by the bore 15.

70 A slide 18 is provided with a pair of contacts 19—19 which extend transversely through the slides and terminate in flush relation with opposite sides of the same.

This slide is adapted for reciprocatory movement within the bore 15 in a manner so as to cause the contacts 19—19; 17—17 and the contact 16—16, for effecting a closed circuit.

75 The flange 10 of the cover is formed with an opening registerable with the open inner end of the hollow projecting 4 and a second opening at the opposite side of the cover registerable with the bore of the boss 3.

The slide 18 is provided at one end with a longitudinally projecting guide rod 20, which is adapted to have its outer end portion projected through the opening in the cover flange and for inserted disposition within the hollow projection 4, when the slide 18 is moved to 95 contacting relation with the contact 17 respectively.

A coiled spring 21 convoluted about the guide rod 20, is adapted to have one end thereof bear against the flange of the cover, while 100

its opposite end bears against the adjacent end of the slide 18, for tensionally maintaining the opposite end of the slide in contact with the opposite portion of the flange and in open circuit position.

5 For the purpose of shifting the slide to closed position, a key 22 is insertible through the bore of the boss 3 so that its end portions will engage in a socket or suitable recess in 10 the adjacent end of the slide. The boss 3 is formed with a bayonet slot 23, or in fact any similar formation, that may receive a pin 24 on the key, when the key has been forced inwardly and turned in the proper direction.

15 Obviously, when the key is moved inwardly, the slide 18 will be shifted in the bore 15, against the tension of the spring 21, by which movement, the guide rod 20 will engage in the hollow projection 4 through an opening

20 in the flange 10. By turning the key slightly in the proper direction, the pin 24 will engage in the offset slot of the bayonet slot 23, whereby the slide will be maintained in closed position with its contact in engagement with the contacts 16 and 17 respectively.

When it is desired to remove the cover, the key 22 is removed so that the slide 18 will be urged to the position shown in Fig. 1, by the 30 tension of the spring 21. In this position, with the key 22 removed, the cover may be lifted from its connection with the housing. Thus it will be seen that the circuit is broken and complete access available to all parts of 35 the structure.

Having thus described my invention, what I claim as new is:—

1. In a switch structure comprising, a housing open at one side, a cover for said housing, 40 said cover being provided with a rectangular shaped flange at its inner side, said flange being adapted to snugly fit within the housing, a slidable contact member carried by said cover at its inner side, a member at one 45 end of the slidable contact for interlocking the cover flange with the housing, tensional means for normally maintaining the contact member in opening position, and means for moving and locking the slidable contact in closed 50 position.

2. A switch structure comprising a housing, said housing being open at one side, a cover for the open side of the housing, a switch member movable within said housing, a bolt 55 carried by the switch member for securing the cover to the housing, and a key for securing the cover to the housing, said key being operable to move the said switch member to closed position.

60 3. A switch structure comprising a housing, said housing being open at one side, a cover for the open side of the housing, a switch member movable within said housing, a bolt carried by the switch member for securing the 65 cover to the housing, a key for securing the

cover to the housing, said key being operable to move the said switch member to closed position, and complementary means between the key and the housing for retaining the switch member in closed position.

70 4. A switch structure comprising a housing, said housing being open at one side, a cover for the open side of the housing, a switch member movable within said housing, a bolt carried by the switch member for securing the cover to the housing, a key for securing the cover to the housing, said key being operable to move the said switch member to closed position, and complementary means between the key and the housing for retaining the switch member in closed position, and spring 75 means for moving the switch member to open position when the complementary means is released.

80 In testimony whereof I affix my signature. 85
JAMES F. MACWILLIAMS.
